CLAIM

The ornamental design for a pressure valve for a bidet washing apparatus as shown and described.

DESCRIPTION

FIG. 1 is a top plan view of a pressure valve for a bidet washing apparatus;

FIG. 2 is a front view of a pressure valve for a bidet washing apparatus;

FIG. 3 is a right side view of a pressure valve for a bidet washing apparatus;

FIG. 4 is a left side view of a pressure valve for a bidet washing apparatus;

FIG. 5 is a rear side view of a pressure valve for a bidet washing apparatus;

FIG. 6 is a bottom side view of a pressure valve for a bidet washing apparatus;

FIG. 7 is an exploded front side view of a pressure valve for a bidet washing apparatus;

FIG. 8 is an exploded top front side view of a pressure valve for a bidet washing apparatus;

FIG. 9 is an exploded bottom front side view of a pressure valve for a bidet washing apparatus;

FIG. 10 is a top front side view of a pressure valve with an opened cap and an opened chamber for a bidet washing apparatus;

FIG. 11 is a top front side view of a pressure valve with a half opened cap and a half opened chamber for a bidet washing apparatus; and,

FIG. 12 is a top front side view of a pressure valve with a closed cap and a closed chamber for a bidet washing apparatus.
